AUTOMATIC GUN

Alfred Krum, Dusseldorf-Eller, and Heinrich Herlach, Berlin-Frohnau, Germany, assignors to Rheinmetall-Borsig Aktiengesellschaft, Berlin, Germany, a corporation of Germany

Application April 25, 1939, Serial No. 269,992
In Germany November 8, 1934

8 Claims. (Cl. 89—37)

The invention relates to automatic guns and more particularly to the mountings for automatic guns comprising a casing with two parts which are adapted to be moved pivotally relatively to each other about an axis parallel to the axis of the bore, to facilitate removing or exchanging the barrel.

Such guns, which can also be used independently of the mounting, are usually recoilably held in easily detachable manner in the mounting by means of front and rear holding members. It is an object of the present invention to facilitate rapid changing of the barrel and to render this operation easy without having to remove the gun as a whole from the mounting.

According to the invention the front bearings of the gun mounting, carrying with them the barrel part of the gun, are arranged so as to be able to swing out laterally about a common axis. Releasable catches which must be operated to permit this movement, are preferably controlled in common by a single handle. By suitably constructing the catches a gun barrel which is to be changed can be freed by a single manipulation and swinging movement.

One typical embodiment of the invention is shown in Figs. 1-3 of the accompanying drawings, and a second in Figs. 4-8.

Figs. 1 and 2 show, in elevation and plan, a light machine gun with the upper part of a gun mounting; Fig. 3 is a cross sectional view of the front bearing of the gun mounting on an enlarged scale taken on line III—III of Fig. 1.

A modified construction is shown in Fig. 4 which is a part sectional plan of the gun and gun mounting in question.

Fig. 5 is a cross-section through the front bearing of the gun mounting on the line V—V of Fig. 4.

Fig. 6 is a cross-section on the line VI—VI, and

Fig. 7 on the line VII—VII of Fig. 4.

Fig. 8 shows the device for releasing the barrel when the parts are moved into the barrel-dismounting position.

The gun casing *a*, Figs. 1 and 2, is subdivided transversely in known manner at the plane *x*—*x* (Fig. 1) at the rear end of the barrel. The front part *a*₁ of the casing which is located in front of the plane of division *x*—*x*, is adapted to be swung out laterally relatively to the rear part *a*₂ about a pin *a*₃ (Fig. 2). The gun casing *a* rests as a whole, and so as to be able to recoil thereon, on the gun support *b*₁ of the gun mounting *b*, and is attached to front and rear slide members

*b*₃, *b*₂ of the gun support by means of clamping rings *c*, *c*₁. The front clamping ring *c* is arranged to be pivotally connected with the member *b*₃ by a bolt *c*₂ which is coaxial with the pin *a*₃ of the casing, and is adapted to be moved from its normal position when the gun is "closed" to its "open" position indicated by broken lines in Fig. 3. A spring catch device *c*₃, *c*₄, *c*₅ provided in the clamping ring *c* secures it in its normal position.

Owing to the coaxial relation of the pivots *a*₃ and *c*₂ the front part *a*₁ of the gun casing, together with the clamp ring *c* embracing it, can, after disengagement of the spring catch *c*₃ by means of the handle *c*₆, be swung, relatively to the rear part *a*₂ of the casing which remains unmoved in the gun mounting, into a position in which the barrel can be drawn, unhindered by parts of the gun or gun mounting, out to the rear.

In the second form of construction shown in Figs. 4-8, the front casing part *a*₁ of the gun (Fig. 4) can be swung after disengagement of a catch *d*, into a side position relatively to the rear part *a*₂ of the gun casing, this movement taking place about a longitudinal pivot *a*₃ disposed axially parallel to the axis of the gun, so that the barrel can be withdrawn to the rear. The bearing *c* is also adapted to pivot about the pivot *c*₂ on the gun mounting while maintaining its coaxial relation with the part *a*₁ of the casing. This pivot *c*₂ is carried on the slide *b*₃ mounted on the tubular gun support *b*₁ and the bearing *c* itself consists of the lower half *c*₀ which is formed as a single member and an upper clamp device which is subdivided into the two clamping members *c*₆, *c*₇ and which is provided with a locking device *c*₈, *c*₉ of the type known per se and usual with flange closures.

The bearing *c*, when the gun is inserted, is normally secured to the slide *b*₃ by a retaining claw *c*₃ (Fig. 5), which is firmly connected with a pin *e* by a pin *e*₁ which runs parallel with the pivot *c*₂ and which in its turn rests rotatably in the bearing half *c*₀, and by a cross-arm *f* fixed to the pivot *c*₂. The shaft *e* is biased to rotate, by means of a pressure member *e*₃ and the spring *e*₂ acting on the projection *e*₄ (Fig. 7), in such a manner that the retaining claw *c*₃ engages the slide *b*₃ and the gun bearing *c* is secured against relative movement. Opposite the casing coupling member *d* of the gun when clamped in the mounting, the pin *e* carries a lever *g* (Figs. 4 and 6) which is firmly connected therewith by a pin *e*₅ and which has a pressure finger *g*₁ which projects towards the gun and co-operates with a

spring pressed member *d*. On the outer end of the lever *g* is mounted a slideable handle *h*, which, when in its neutral position, is pressed by a spring *h*₁ to cause a locking nose *h*₂ to engage under a locking claw *b*₄ provided on the slide *b*₃, and in this position the pin *e* is locked against unintentional rotary movement.

The gun mounting slide *b*₃ carries, at the hinge side of the front gun bearing *c*, a supporting tray *b*₅ (Figs. 4 and 5) which receives the casing part *a*₁ when the latter has been swung with the pivoted bearing *c* into the barrel-removal position. Moreover, on the slide *b*₃ or elsewhere on the gun mounting, there is provided a spring-urged plunger stop *k* (Figs. 4 and 8). When the gun is swung to the "open" position the stop *k* co-operates with a bell-crank lever *i* on the front part *a*₁ of the casing. The lever *i* is then swung against the action of a spring *i*₁ and thereby strikes against the barrel which is thereby thrust rearwardly for a certain distance out of its casing *a*₁ so that it can be gripped.

The clamping of the gun which recoils as a whole on the gun mounting, the rear part of the casing resting in a second vise-like bearing, is not affected by the changing of the barrel. To exchange a barrel which has been fired until it has become hot, with a new one, the gunner, behind the gun first presses the handle *h* inwards against the influence of the spring *h*₁ until it disengages from the retaining claw *b*₄, then obliquely upwards, the pin *e* being then turned whereby, and when turned the coupling member *d* and the catch *c*₃ are disengaged. Further pressure on the handle *h* now causes the bearing *c*, together with the front part *a*₁ of the gun casing, to pivot about the pin *c*₂ and about the pin *a*₃ coaxial therewith. Shortly before the part *a*₁ comes into position on the supporting tray *b*₅, the lever *i* strikes the spring stop *k* on the gun-mounting and it is thereupon swung so as to move the barrel slightly out of its casing. The lever *i* under the influence of its spring *i*₁, immediately returns into its initial position, thrusting the spring stop *k* back against the influence of the spring *k*₁. A new barrel can now be introduced into its proper front position in the casing part *a*₁. After the barrel has been changed, the bearing member *c* may be swung back, whereby all the catches—the gun catch *d*, the catch *c*₃, and the handle catch *h*₂—re-engage automatically. The gun is again in its correct position on the gun-mounting and ready for firing.

We claim:

55. 1. A machine gun and a mounting in which it is adapted to be used, said gun having a front casing part supporting the barrel of the gun and a rear casing part supported by said mounting, joint means between said parts whereby the front casing part can be swung transversely to the barrel axis into a position out of alignment with the rear casing part to permit removal of the gun barrel from said front part, and a bearing pivoted on said mounting about an axis parallel to the barrel axis and in alignment with the axis of said joint means, said bearing supporting said front casing part forwardly of the joint means.

70. 2. A machine gun and a mounting in which it is adapted to be used, said gun having a front casing part supporting the barrel of the gun and a rear casing part supported by said mounting, joint means between said parts whereby the front casing part can be swung transversely to the barrel axis into a position out of alignment with the rear casing part to permit removal of the gun

barrel from said front part, a bearing pivoted on said mounting about an axis parallel to the barrel axis and in alignment with the axis of said joint means, said bearing supporting said front casing part forwardly of the joint means, means for locking said bearing to the mounting in the position of alignment of said front and rear casing parts with each other, and means for releasing the locking means and also rocking said bearing and front casing part into barrel removing position.

3. A machine gun and a mounting in which it is adapted to be used, said gun having a front casing part supporting the barrel of the gun and a rear casing part supported by said mounting, joint means between said parts whereby the front casing part can be swung transversely to the barrel axis into a position out of alignment with the rear casing part to permit removal of the gun barrel from said front part, a bearing pivoted on said mounting about an axis parallel to the barrel axis and in alignment with the axis of said joint means, said bearing supporting said front casing part forwardly of the joint means, means for locking said front casing part with said rear casing part in their aligned position, means for locking said bearing to the mounting in the position of alignment of said parts, and a single release means operative on both said locking means.

4. A machine gun and mounting according to claim 3, in which the release means comprises a handle and a shaft mounted in the front casing part.

5. A machine gun and a mounting in which it is adapted to be used, said gun having a front casing part supporting the barrel of the gun and a rear casing part supported by said mounting, joint means between said parts whereby the front casing part can be swung transversely to the barrel axis into a position out of alignment with the rear casing part to permit removal of the gun barrel from said front part, a bearing pivoted on said mounting about an axis parallel to the barrel axis and in alignment with the axis of said joint means, said bearing supporting said front casing part forwardly of the joint means, means for locking said bearing to the mounting in the position of alignment of said front and rear casing parts with each other, means for releasing the locking means and also rocking said bearing and front casing part into barrel removing position, and catch means on the mounting for releasably engaging said release member.

6. A machine gun and a mounting in which it is adapted to be used, said gun having a front casing part supporting the barrel of the gun and a rear casing part supported by said mounting, joint means between said parts whereby the front casing part can be swung transversely to the barrel axis into a position out of alignment with the rear casing part to permit removal of the gun barrel from said front part, a bearing pivoted on said mounting about an axis parallel to the barrel axis and in alignment with the axis of said joint means, said bearing supporting said front casing part forwardly of the joint means, barrel ejecting means, and a stop on the gun mounting for operating said ejecting means when said front casing part is swung out of alignment with said rear casing part.

7. A machine gun and a mounting in which it is adapted to be used, said gun having a front casing part supporting the barrel of the gun and a rear casing part supported by said mounting, joint means between said parts whereby the front

- casing part can be swung transversely to the barrel axis into a position out of alignment with the rear casing part to permit removal of the gun barrel from said front part, a bearing pivoted on said mounting about an axis parallel to the barrel axis and in alignment with the axis of said joint means, said bearing supporting said front casing part forwardly of the joint means, barrel ejecting means, a stop on the gun mounting for operating said ejecting means when said front casing part is swung out of alignment with said rear casing, and a spring for restoring the barrel ejecting means to normal position after its operation by the stop.
15. 8. A machine gun and a mounting in which it is adapted to be used, said gun having a front casing part in which the gun barrel is removably attached and a rear casing part supported by said mounting, joint means between said front and rear parts whereby the front casing part can be swung transversely to the axis of the barrel into a position out of alignment with the rear casing part allowing removal of said barrel, a bearing pivoted to said mounting about an axis parallel to the barrel axis and in alignment with the axis of the joint means, said bearing supporting said front casing part forwardly of the joint means, means for locking said bearing to the mounting in position of alignment of said front and rear casing parts, means for locking said front casing part with said rear casing part in their 10 aligned position, release means comprising a handle and a shaft mounted in said front casing parts, said shaft operating both said locking means and said handle on continued operation after release of both said locking means being 15 adapted to swing said front casing part into barrel removing position, and means for releasably locking said handle to the mounting when the gun is in condition for use.
